ELECTRIC GRILL

Traugott Oertli, Zurich, Switzerland

Application December 28, 1950, Serial No. 13,609

Term of patent 7 years

(Cl. D81—10)

To all whom it may concern:

Be it known that I, Traugott Oertli, a citizen of the Confederation of Switzerland, and residing in Zurich, Switzerland, have invented a new, original, and ornamental Design for an Electric Grill, of which the following is a specification, reference being made to the accompanying drawing, forming part thereof.

Fig. 1 is a top plan view of the electric grill showing my new design;

Fig. 2 is a front elevational view of the electric grill shown in closed position;

Fig. 3 is a view similar to that of Fig. 2 with the grill in partly open position;

Fig. 4 is a side elevational view of the grill in closed position;

Fig. 5 is a perspective view thereof in open position and on a slightly reduced scale.

I claim:

The ornamental design for an electric grill, substantially as shown.

TRAUGOTT OERTLI.
